UNITED STATES PATENT OFFICE.

HARRY M. GAIL, OF BUFFALO, NEW YORK.

TELEPHONE-TRANSMITTER.

SPECIFICATION forming part of Letters Patent No. 790,428, dated May 23, 1905.

Application filed July 7, 1904. Serial No. 215,563.

To all whom it may concern:

Be it known that I, HARRY M. GAIL, a citizen of the United States, residing at Buffalo, in the county of Erie and State of New York, have invented new and useful Improvements in Telephone-Transmitters, of which the following is a specification.

This invention relates more particularly to that class of telephone-transmitters or microphones in which a granular conductor or resistance, such as powdered carbon, is interposed between the electrodes. In transmitters of this character as heretofore constructed the carbon granules in course of time became packed, which impaired the operation of the transmitter.

One of the objects of this invention is to so organize the transmitter that the carbon granules are automatically shaken during the ordinary use of the instrument, thereby keeping the carbon loose and in the highest state of efficiency.

Another object of this invention is to provide a transmitter which has greater power and volume, which reproduces the same waves more clearly, and in which the sound-waves are prevented from reverberating.

This invention has the further object to improve the construction of the transmitter with a view of simplifying the parts, reducing its cost, and also giving the same a neat appearance.

In the accompanying drawings, Figure 1 is a front elevation of my improved transmitter. Fig. 2 is a vertical section of the same, taken lengthwise through the axis thereof and showing the mouthpiece turned in a vertical position. Figs. 3 and 4 are vertical cross-sections taken in lines 3 3 and 4 4, Fig. 2, and showing the mouthpiece turned in a horizontal position. Fig. 5 is a fragmentary side elevation of one of the supporting-arms of the transmitter.

Similar letters of reference indicate corresponding parts throughout the several views.

The housing or casing of the transmitter consists of a tubular shell or cylindrical body A, of metal, the axis of which is horizontal, and two heads or caps a a, applied to opposite ends of the body. The space within the

casing is divided by metal partitions or disks B B into a central chamber, which is arranged between the partitions and two end chambers, each of which is arranged between one of the partitions and the adjacent head or cap of the casing. The partitions and caps may be secured to the body in any suitable manner, but preferably by threading the bore of the body and screwing the partitions and caps into the body. The caps are preferably held against displacement in the body by set-screws a' or otherwise.

C represents the mouthpiece of the transmitter, which is bell-shaped or flaring and has its outer large end projecting laterally from the side of the body, while its small end projects transversely inward through an opening in the body into the central chamber of the same. Within the central chamber is arranged a sound-distributer D, comprising two branch tubes or conduits d d, whereby the interior of the mouthpiece is connected with the end chambers. The branch tubes unite in a laterally-projecting nozzle of the sound-distributer, which nozzle is connected by a screw-sleeve e with the small end of the mouthpiece. From the mouthpiece the branch tubes diverge and terminate in nozzles, each of which projects axially through a central opening b in one of the partitions. Around its axial nozzles the sound-distributer is provided with annular shoulders d', which bear against the inner side of the partitions, whereby the distributer serves as a space-block for maintaining the partitions in the proper position relatively to each other and the distributer.

Each of the end chambers contains a complete transmitting device, both of which are identical in construction, and the following description of one will therefore apply to both: F is a diaphragm, of aluminium or other suitable material, which is clamped at its margin between the marginal part of the adjacent partition and the corresponding cap. A washer or packing-ring f, of rubber or similar material, is preferably interposed between the diaphragm and the adjacent cap for producing a uniform bearing and firmly gripping the diaphragm around its entire margin. The marginal part of the partition is raised, so that

the central part of the diaphragm is held out of engagement from the partition and is free to vibrate under the action of the sound-waves, which are directed against the same by 5 the distributor from the mouthpiece.

G H represent a pair of coöperating electrodes, consisting of disks of carbon or similar material, which are arranged axially within each of the end chambers and opposite each 10 other. The inner electrode G is secured centrally to the adjacent diaphragm by a bolt *g*, a washer *g'* being preferably arranged on this bolt between the diaphragm and the inner electrode. The outer electrode H is secured 15 to the adjacent cap of the casing by a bolt I, which passes axially through a central opening in said cap, but is insulated therefrom. The head *i* of this bolt bears against the inner side of the cap, but is insulated therefrom 20 and carries the outer electrode H, while its nut *i'* bears against the outer side of said cap. The outer electrode may be fastened to the bolt-head *i* in any suitable manner—for instance, by electroplating the back of the electrode 25 and then soldering the same to the bolt-head. Surrounding the pair of electrodes is a retaining-sleeve J, of felt or similar fibrous material, which extends from the diaphragm to the corresponding cap of the casing. A 30 cylindrical cell is thus formed between the companion electrodes, which is filled with a granular conductor or resistance *j*, such as powdered carbon or other electrical conducting substance of granular form.

35 The main operating parts of the transmitter thus far described are mounted in any suitable manner on a support, so that the same may be rocked or turned in a vertical plane for adjusting the mouthpiece to the speaker.

40 The preferred means for this purpose consists of two angular conducting-arms *k k'*, of metal, secured at their lower ends by screws *l l* to opposite sides of a support or standard L, constructed of insulating material. This standard may form part of a stand for supporting 45 the transmitter on a desk in the usual manner. The upper end of each arm is provided with a circular opening or bearing *m*, in which is journaled a trunnion *m'*, which is formed concentrically on the outer end of the adjacent screw-nut *l'*.

50 One side or line, *n*, of the electric circuit containing the transmitter is connected with one of the conducting-arms of the support, while 55 the other side or line, *n'*, of said circuit is connected with the companion arm. Instead of mounting the transmitter on a standard the same may be similarly mounted on a wall or any other suitable way.

60 The electric current entering one of the lines passes from the same successively through the adjacent supporting and conducting arm, trunnion, outer bolt, outer electrode, powdered carbon, inner electrode, inner bolt, diaphragm, 65 and partition on one side of the transmitter,

thence crosses through the body of the casing and passes successively through the partition, diaphragm, inner bolt, inner electrode, powdered carbon, outer electrode, outer bolt, trunnion, and supporting-arm on the other 7c side of the transmitter and out through the other line.

The sound-waves produced by speaking into the mouthpiece are directed by the branch tubes of the distributor so as to impinge perpendicularly against the diaphragms, whereby the latter owing to their resilience are caused to vibrate and alternately compress and release the carbon granules, thereby setting up 75 pulsations or undulations in the electric current, whereby the speech is transmitted to the receiving instrument connected with this circuit in a well-known manner. The fibers of the retaining-sleeves are sufficiently close to 80 confine the carbon granules between the electrodes and bear firmly enough against the diaphragms so as to act as dampers for preventing false vibrations thereof. 85

When persons of different stature use the transmitter, they raise or lower the mouthpiece to the required position most convenient for use, whereby the transmitter is turned or rocked bodily in a vertical plane on its support. Inasmuch as the horizontal axis of the supporting-trunnion is coincident with that of 90 the diaphragms and the cells containing the carbon granules, this rotary movement of the transmitter causes the granules to be tumbled or agitated, thereby keeping the same loose and in proper working condition. Owing to 95 the fact that the turning of the transmitter is incidental to adjusting the mouthpiece to the speaker the carbon granules are agitated involuntarily by each speaker who shifts the transmitter, and as this occurs very frequently 100 the granules are not permitted to become packed and impaired in operation, but are maintained in a condition of highest efficiency. By thus automatically shaking the granules 105 at comparatively short intervals the transmitter is prevented from losing its original power after long and continued use and the expense of keeping the same in repair or adjustment 110 common to other types of transmitters is avoided. 115

In order to permit the transmitter to remain in any position to which it may be adjusted, the weight of the mouthpiece is offset by a counterbalancing-weight *o*. The latter is preferably secured by screws *o'* or otherwise on the inner side of the body diametrically opposite the mouthpiece, as shown in Fig. 3. The balancing-weight *o* is preferably of such width that its sides are engaged by the marginal parts of the partitions when the same are screwed into the body, as shown in Fig. 2, thereby serving to properly space the partitions in addition to balancing the transmitter. 120

125 As shown in Fig. 2, the division-wall or 130

partition ρ between the branch tubes of the distributor extends forwardly beyond the outlet ends of both branch tubes. By this means the sound-waves leading to each diaphragm 5 are maintained distinct or separate and prevented from reverberating from one diaphragm to the other, thereby insuring more perfect transmission of speech.

The washer between either diaphragm and 10 the corresponding inner electrode may be replaced by one of greater or lesser thickness for adjusting the distance between each pair of electrodes and causing the same to bear properly against the granules between the same.

15 By attaching the electrical terminals to the supporting-arms and conducting the current from the latter through the trunnions of the transmitter the use of wires in the transmitter is avoided, thereby preventing interruption 20 in the electric current and rendering the working of the instrument absolutely reliable.

If desired, the transmitting devices in one side of the casing may be omitted; but it is preferable to employ both and connect the 25 same in series in the manner described. By this means the power of the transmitter is increased, thereby rendering the same especially desirable for long-distance service. Furthermore, by duplicating the transmitting 30 devices the instrument is less liable to become totally disabled, because conversation can still be carried on through one of the transmitting devices if the other should become inoperative for any reason. When 35 either side of the transmitter becomes inoperative, the same may be removed for repairs and replaced without disturbing the other side of the transmitter and without disconnecting any wires.

40 My improved transmitter as a whole is exceedingly simple and inexpensive in construction, reliable in operation, and has no delicate parts which are liable to get out of order.

Although I have herein shown the preferred embodiment of my invention, it is obvious that the same may be varied without departing from the scope of the invention.

I claim as my invention—

1. A transmitter comprising a cylindrical body having its bore threaded, caps screwed 50 into opposite ends of the body, partitions screwed into the body and dividing the same into a central chamber and two end chambers, a mouthpiece extending transversely through the body into the central chamber, a 55 distributor arranged in the central chamber and having branch tubes extending from said mouthpiece through the central openings in the partitions, diaphragms arranged in the end chambers next to the partitions, a pair of 60 electrodes arranged in each end chamber and having its members connected respectively with the adjacent diaphragm and cap, a fibrous sleeve surrounding each pair of electrodes and forming a cell between the same, and a 65 granular body arranged in each cell, substantially as set forth.

2. A transmitter comprising a tubular body the axis of which is arranged horizontally, caps arranged at opposite ends of the body, 70 diaphragms arranged vertically in the body, a mouthpiece mounted on the body and having branches leading to said diaphragms, bolts extending axially through the caps and having their heads arranged within the casing 75 while their nuts are arranged outside thereof, two pairs of electrodes the inner members of which are connected with the diaphragms while the outer members are secured to said bolt-heads, a retaining-sleeve surrounding each pair of electrodes and forming a cell between the same, a body of granular material arranged in each cell, a trunnion formed on each of said nuts, and a support 80 consisting of an insulating-standard and two 85 conducting-arms which are secured at their lower ends to said standard and are provided at their upper ends with bearing-openings in which said trunnions are journaled, substantially as set forth. 90

Witness my hand this 1st day of July, 1904.
